UNITED STATES PATENT OFFICE.

DAVID SILBERMAN, OF NEW YORK, N. Y.

HOOK AND EYE TAPE.

Application filed August 19, 1924. Serial No. 732,955.

To all whom it may concern:

Be it known that I, DAVID SILBERMAN, a citizen of the United States, residing in the city, county, and State of New York, have invented certain new and useful Improvements in Hook and Eye Tapes, of which the following is a specification.

My invention relates to hook and eye tapes and it is my object to produce a sewed tape which will be stronger than any now on the market, which will be free from pockets from which the hooks or eyes may slide rearwardly, in which the bases of the hooks or eyes are firmly locked to the tape so they cannot buckle under strain, which tape can be simply and cheaply produced without an investment for expensive automatic machinery for riveting or slitting, in which manual handling is entirely eliminated in the process of manufacture, the cloth strips being fed to a sewing machine wherein the folds are made, the hooks or eyes fed and affixed and the finished product finally rolled up ready for the market. A further object is the production of a strong hook and eye tape from strips of fabric cut from width goods instead of using the more expensive specially woven selvage edge tape and in which the hooks or eyes are solidly held against displacement in any direction solely by stitching or sewing.

In the drawing Fig. 1 is a plan view of the preferred form of the hook member of my improved tape, with a corner turned down; Fig. 2 a like view of the eye member; Fig. 3 a plan view of a hook member showing a modified form of stitching around the hook base; Fig. 4 a like view of a tape with zig-zag stitching; Fig. 5 a like view of a selvage edge tape with a straight line of stitching extending around the hook base; Fig. 6 a view of a modified form of tape composed of two separate tapes or strips of fabric; Fig. 7 a sectional view of the structure of Figs. 1 and 3 on the line 7-7 thereof; Fig. 8 a sectional view of the structure of Fig. 6 on the line 8-8 thereof, and Fig. 9 is a sectional view of my improved tape taken through one of the fasteners.

In the preferred form of the hook member shown in Fig. 1, which is the cheapest form from a production viewpoint, a strip of fabric 1 is cut from piece goods. This strip is folded to form flaps 2 and 3, the flap 2 being wider than the flap 3. The raw edge of the outer flap 2 is folded under at

4 as shown in Figs. 1 and 7 to finish the exposed edge. Hooks 5 are spaced along the strip with their bases 6 between the open edges of said flaps and a line of stitching 7 or sewing 7 is run along near the edge of the flap 2 and passes through the turned over edge 4, flap 3 and strip 1, serving to unite the parts. When the needle reaches the hooks 5, which have been automatically positioned, the thread passes around the forward part of the base at 8, then jumps over to the central arms at 9, and around them, then back to the forward part of the base at 8' and around it, thence running along the edge of the flap to unite the parts.

In Fig. 2 I have shown the preferred form of eye member. The strip of fabric is formed as in the hook member but the line of stitching 10 running along the edge of the flap 2 goes around the forward ends of the base of the eyes 11 at 12 and 12' and closes the space 13 in the opening at the base of the eye proper so that no pocket is formed.

As the stitching passes through four thicknesses of fabric and around the hook or eye bases the hooks or eyes are solidly united to the fabric and cannot move or buckle and a much stronger product results. If desired the open edges of the flaps 2 and 3 may be still further folded over to take the stitching through an increased number of plies thereby increasing the strength of the tape.

In Fig. 3 I have shown the tape folded as in Figs. 1, 2 and 7 but the stitching 7' extends entirely around the outer portion of the hook bases at 14.

In Fig. 4 I have shown how a zig zag stitch 15 may be used to sew the flaps together and extend around the hook bases.

In Fig. 5 I have shown how a selvage edge tape may be used without turning in the edge of the flap 2' to produce a finished edge, the line of stitching being like that shown in Fig. 3.

In Fig. 6 I have shown how two strips of fabric 16 and 17 may be folded over as shown in section in Fig. 8 so that the edge 105 of a garment may be inserted between the flaps 18 and 19 and the three parts sewed together, the line of stitching 20 holding the two strips together and locking the hooks in place.

As all the operations of folding the strip, feeding and positioning the hooks or eyes

and sewing the parts together are done automatically in a special sewing machine there is no manual handling of the separate parts. The use of expensive automatic riveting machinery is eliminated and the use of expensive slitting machines is obviated, both of which were necessary in making the tapes of the prior art.

My tape, thus produced, has no pockets for the hooks or eyes and from which they slide backwardly and become displaced. As no rivets are used the bases of the hooks or eyes cannot spread under side strains and pull off the rivets. As the bases are solidly sewed to the strip they cannot buckle and pull off under side strains. As no slitting of the fabric occurs there is no weakening from this cause. The sewed tape made according to my present invention is the strongest yet produced and can be more cheaply produced than any yet placed upon the market.

By the term fastening member in the claims I mean either the hook or the eye member co-operating therewith.

I claim:—

1. Hook or eye tape comprising two plies of imperforate fabric forming flaps, wire

fastening members provided with base loops, said base loops lying between the open edges 30 of the flaps with their engaging portions extending beyond a flap and a line of stitching extending along the flaps and uniting them, said stitching including stitches extending transversely of said line and encircling the wire of the base loops whereby the fastening members are securely locked between the flaps.

2. Hook or eye tape comprising two plies of imperforate fabric forming flaps, the 40 edge of each flap being turned under, wire fastening members provided with base loops, said base loops lying between the open edges of the flaps with their engaging portions extending beyond a flap and a line of stitching 45 extending along the flaps and passing through the folded under edges uniting them, said stitching including stitches extending transversely of said line and encircling the wire of the base loops whereby the fastening members are securely locked between the flaps and their folded under edges.

In testimony whereof I have hereunto subscribed my signature.

DAVID SILBERMAN.
